UNITED STATES PATENT OFFICE.

WILLIAM E. SCHIEBLE, OF MIAMISBURG, OHIO, ASSIGNOR TO D. P. CLARK AND COMPANY, OF DAYTON, OHIO, A COPARTNERSHIP.

RAILWAY SIGNAL SYSTEM.

No. 827,122.

Specification of Letters Patent.

Patented July 31, 1906.

Application filed March 24, 1905. Serial No. 251,749.

To all whom it may concern:

Be it known that I, WILLIAM E. SCHIEBLE, a citizen of the United States, residing at Miamisburg, in the county of Montgomery and State of Ohio, have invented certain new and useful Improvements in Railway Signal Systems, of which the following is a specification, reference being had therein to the accompanying drawings.

This invention relates to railway signal systems, and more particularly to that class known as "electric signal systems," being designed for use more particularly in connection with electric railways.

The invention is in the nature of an improvement upon the construction set forth in Letters Patent No. 786,604, granted to me April 4, 1905; and has for its objects, among other things, first, to reduce the number of wires required between signal-stations, so that a single wire may be employed instead of the larger number required in the construction set forth in my said prior patent, and, second, to provide a more efficient contact structure for the commutators and one which will effectually prevent "overthrow" or excessive movement of the commutators beyond the prescribed limit.

To these and other ends my invention consists in certain novel features, which I will now proceed to describe and will then particularly point out in the claims.

In the accompanying drawings, Figure 1 is a plan view in the nature of a diagram, illustrating the application of my invention to a single-track railroad having turnouts or passing-sidings at intervals. Fig. 2 is a front elevation of so much of the system as relates to one complete block or section. Fig. 3 is a plan view of what is shown in Fig. 2. Fig. 4 is a transverse sectional view of one of the rotatory switches or commutators, taken on the line *xx* of Fig. 3 and looking in the direction of the arrows. Fig. 5 is a longitudinal sectional view of the same, taken on the line *yy* of Fig. 4 and looking in the direction of the arrows; and Figs. 6, 7, 8, and 9, are diagrammatic views illustrating various positions of the parts.

The particular embodiment of my invention which I have chosen for purposes of illustration is one in which the system is used in connection with the trolley-wire or feed-wire of an electric railway as a source of current

supply, the same being indicated by the reference-numeral 1. The main track of the railway is indicated at A in Fig. 1, the same being provided with turnout-tracks B C, &c., at suitable intervals. The space between two of these turnouts constitutes a block or section and is protected by a separate and independent signaling structure, one of which is shown complete in Figs. 2 and 3 of the drawings. Each of these signaling structures comprises a signaling station at each end, (indicated in the present instance by the reference-letters D and E,) their location, as shown in Fig. 1, being at the junctures of the turnouts with the main line. Each station comprises a suitable upright or support 2, located at the side of the track and having mounted on it a commutator 3, so placed that it will not be readily accessible to the public, while it will be adapted to be engaged and actuated by a suitable projecting member carried by the car. Each commutator is preferably constructed in the manner shown in detail in Figs. 4 and 5 of the drawings, having a body 4 of insulating material substantially cylindrical in form and mounted upon an axis 5, preferably a conducting material, on which axis it is free to rotate. The peripheral portion of the commutator is provided at intervals with contact-pieces 6, which are in electrical connection with the shaft or axis 5 by connecting-pieces 7 at the inner end of the commutator. The insulating-body of the commutator is exposed at intervals between the contact-strips 6 and is recessed or hollowed out, as shown at 8, these recesses alternating with the strips 6.

In connection with each commutator I employ two contact-arms 9 and 10, pivoted to the support 2 at 11, said arms depending on opposite sides of the commutator and being so arranged relatively thereto that when one of them is in contact with one of the conducting-strips 6 the other will be in contact with the insulated body of the commutator. In order to insure a proper contact of these arms with the commutator, their lower ends are weighted, and I prefer for this purpose the construction shown, in which a single weight 12 is employed, connected to both arms by links 13, the connection between said arms at their lower ends being an insulated one. As a simple and efficient means for effecting this insulation I insert the ends of the

links 13 whereby they are pivoted to the weight 12 into sleeves or bushings 14, of insulating material. Each contact-arm preferably has that portion thereof which comes 5 into actual contact with the commutator made in the form of a roller 15, so as to reduce the friction and wear. One of the contact-arms—as, for instance, the arm 9—is connected by a wire 16 with the supply-wire 1, a binding-post 17 and connecting-strip 18 being employed for conveniencesake between said wire and the pivot of the contact-arm. The other arm (in this case the arm 10) is connected by a wire 19 to ground, a similar binding-post 20 and connecting-strip 21 intervening between the wire and the pivot of the contact-arm. Each commutator is provided with a number of projecting fingers 22, one for each strip 6, and intervening insulated 15 space 8, and these fingers are arranged in the path of the projection on the car, so as to be moved thereby when in contact with the same a distance equal to the space between two adjacent fingers 22.

25 The foregoing description applies with equal force to both stations of each signaling structure. The contact-surfaces of the commutators of the two stations are connected by a wire 23, this connection being preferably 30 effected by connecting the ends of the wire 23 with the rearwardly-projecting ends of the shafts or axes 5. The wire 23 is the only wire connecting the stations, and the signaling-lamps 24 are arranged in series upon said wire, a sufficient number being employed to give the resistance required to effect the result hereinafter set forth.

35 The operation of the system is similar to that of the system set forth in my said prior 40 Letters Patent to the extent that if the signal-lamps are extinguished and a car enters the section from either direction the lamps will be lighted, the lamps being extinguished when said car leaves the section, or, conversely, if the 45 lamps are lighted, a car entering from either end will extinguish them when it enters the section and light them again when it leaves the same. The operation of the system will be best understood by reference to the dia- 50 grammatic views, Figs. 6 to 9, inclusive. In Fig. 6 the parts are shown in the same position in which they are shown in Figs. 2 and 3, the lamps being extinguished by reason of the fact that both of the contact-arms 9, which 55 form the sole connection with the supply-wire 1, are in contact with insulated portions 60 of the two commutators and the lighting-circuit is broken. If a car enters the section from either direction, the position of one of 65 the commutators will be changed either to that shown in Fig. 7 or that shown in Fig. 8. In either case the lighting-circuit is established from the supply-wire 1, through the wire 16, to that one of the contact-arms 9 65 which is in contact with one of the conduct-

ing-strips 6 of the commutator at one of the stations, and thence through the shaft 5 and lighting-wire 23 to the shaft 5 of the commutator at the other station, thence through contact-strips 6 and contact-arm 10 and 70 wire 19 to ground. This establishes the circuit from the supply-wire, through the lamps, to the ground and the lamps will burn. When the car leaves the section, it will turn the commutator of the last station, so that 75 the parts will assume the position shown in the diagram illustrated by Fig. 9, in which position both of the grounded contact-arms are cut out and the lighting-circuit is connected at both of its ends to the supply-wire. 80 The lamps in said lighting-circuit are of a resistance such that the current will not pass through them, so that the lights remain unlighted or do not burn. When another car enters the section from either direction with 85 the parts in the position indicated in Fig. 9, the turning of either commutator will reestablish the lighting-circuit from the supply-wire to the ground through whichever one of the grounded contact-arms is moved onto the 90 contact-strip 6, thus returning the parts once more to either one of the two positions shown in Figs. 7 and 8.

It will thus be seen that the same general results are obtained by my present construc- 95 tion as are obtained by my previously-patented construction, each car properly setting its own signals as it enters and leaves the section. It will further be noted that my present construction requires but a single signaling-wire between the signaling-stations and is 100 therefore simpler and less expensive.

The construction of the contact-arms and commutators is such that the weight draws each pair of contact-arms toward each other, 105 so as to firmly press against the commutator, holding the roller of one arm firmly in contact with one of the strips 6, while the roller of the other arm is pressed firmly into one of the recesses 8. The rollers permit the commutator 110 to turn when one of its fingers is struck by the projection from the car; but as soon as said projection has passed clear of said finger the roller of one of the arms enters into one of the recesses 8 and prevents any further rotation of the commutator, the inertia of which is not sufficient to lift the weight. The employment of a weight to operate the contact-arm is advantageous for the reason that the action thereof is uniform and is not affected 115 by wear, weather, or temperature.

Having thus fully described my invention, what I claim as new, and desire to secure by Letters Patent, is—

1. In an electric signaling system for railroads, a support, a commutator rotatably mounted on said support, contact-arms pivotally suspended from said support on opposite sides of the commutator, and a weight suspended from said arms and acting to draw 125 130

them together toward the commutator, substantially as described.

2. In an electric signaling system for railroads, a support, a commutator rotatably mounted on said support and having alternate peripheral contact-strips and recesses, contact-arms pivotally suspended from said support on opposite sides of the commutator and provided with rollers, one of which bears ⁵ on a contact-strip while the other engages a

recess, and a weight suspended from said contact-arms and acting to draw them forcibly together, substantially as described.

In testimony whereof I affix my signature in presence of two witnesses.

WILLIAM E. SCHIEBLE.
